UNITED STATES PATENT OFFICE.

HARRY C. JENNEY, OF NEW BEDFORD, MASSACHUSETTS.

LEATHER SHOE.

SPECIFICATION forming part of Letters Patent No. 730,919, dated June 16, 1903.

Application filed February 10, 1903. Serial No. 142,775. (No model.)

To all whom it may concern:

Be it known that I, HARRY C. JENNEY, a citizen of the United States, residing in New Bedford, in the county of Bristol and State of Massachusetts, have invented a new and useful Improvement in Leather Shoes, of which the following is a specification.

This improvement relates to that class of shoes in which the quarter is open in front and joined at or below the lower end of the opening to the vamp, said shoes being provided with a tongue or flap at the opening and being ordinarily secured to the foot by lacing. In shoes of this character there has been general complaint, especially by those whose feet are tender, of the bunch or inward protuberance extending against the upper side of the foot and produced by the additional thickness formed by the meeting of the lower ends of the stay tongue and quarter under the vamp-seam immediately below the end of the opening of the vamp. It will be seen, therefore, that just at this point there are four thicknesses of leather—the stay, the tongue, the quarter and the vamp—besides the thickness produced by the seam of the vamp, while just below this point there is but one thickness of leather—viz., that of the vamp. It is evident that in heavy work this objection is comparatively greater, although the complaint as to the additional thickness at this point is quite common by wearers of medium and light shoes.

It is the principal object of my invention to obviate this difficulty by doing away at that point with the lower ends or edges of the stay and quarter and extending only the tongue at its lower end under the vamp without making any radical change in the appearance of the shoe, but adding to the beauty and finish, and at the same time doing away with the principal objection made to lace shoes. Moreover, as in my improvement the quarter does not extend down under the vamp the danger of splitting the vamp down longitudinally is avoided. This splitting occurs in the ordinary construction because the edges of the quarter gap at the lower end under the vamp and strain the vamp at its upper edge at that point, with the effect that the stitches give way and the vamp splits. In my device as the quarter does not extend under the up-

per edge of the vamp there is no opening below the vamp and no strain to split it.

The nature of the invention is fully described in detail below and illustrated in the accompanying drawings, in which—

Figure 1 is a side elevation of a lace shoe embodying my invention. Fig. 2 is a plan view of that portion of the shoe in which the invention or improvement is located. Fig. 3 is a section taken on line X, Fig. 2. Fig. 4 is a plan view of one of the two portions constituting the quarter. Fig. 5 is a similar view of the tongue.

Similar letters of reference indicate corresponding parts.

a represents the vamp; *b*, the quarter; *c*, the stays on the inner surface of the quarter on the opposite sides of the gap or opening *d*; *e*, the tongue.

The front portion of the lower edges of the quarter *b* instead of extending down under the upper edge *a'* of the vamp for a certain distance each side of the opening *d*—say between the points *s*—extend down nearly or quite to said edge, but do not underlap it, the lower edge *b'* of each portion of the quarter practically abutting against the upper edge *a'* of the vamp, as shown in Figs. 2 and 3. The stays *c* on opposite sides of the opening *d* extend down as far as the lower edges of the quarter in substantially the manner indicated in Fig. 3, their lower edges ending within the fold produced by the ordinary seam with which the lower edge of the quarter is preferably provided, a similar seam being preferably provided at the upper edge of the vamp. The lower edge or end of the tongue *e* is broadened at *e'* and extends beyond the lower edges of the two portions of the quarter and stays and underlaps the vamp to a suitable distance, as indicated by dotted lines *e''* in Fig. 2, and is stitched thereto, as represented at *f* in Fig. 3. The tongue therefore produces the only additional thickness of leather which is below or under the vamp. The tongue is stitched not only to the vamp, but to the quarter, the line of stitching which secures it to the quarter being indicated at *g*, Fig. 3, and at *h*, Figs. 1 and 2, there are diagonal stay-stitchings for the purpose of preventing the tongue from breaking away from the quarter at the lower end of the open-

ing. It will be seen that by reason of this construction and arrangement there is no opening below the vamp, as the quarter stops at the upper edge of the vamp, and hence there is no strain or tendency to split the vamp, and that the greater portion of the thickness or bunch produced at or below the upper edge of the vamp is done away with, inasmuch as the tongue only extends across the joint and under the vamp.

Of course it will be understood in examining Fig. 3 of the drawings that the parts are necessarily exaggerated in thickness.

Having thus fully described my invention, what I claim, and desire to secure by Letters Patent, is—

1. In a front-laced shoe, a quarter divided in front to form a lacing-opening, a continuous vamp, free from said quarter for a suitable distance on each side of said lacing-opening, the adjacent edges of said vamp and quarter abutting, and a tongue beneath the quarter and the abutting edges of the vamp and quarter, spanning the lacing-opening, extending a short distance under the vamp, and secured to said vamp and quarter near their abutting edges.

2. In a front-laced shoe, a quarter divided to form a lacing-opening, a continuous vamp, said vamp and quarter having their edges abutting for a suitable distance on each side of the lacing-opening but free from each

other, stays secured beneath the quarter at the edges of the lacing-opening, extending to but not under the vamp, and a tongue beneath said quarter and stays, spanning the lacing-opening, extending a short distance beneath the vamp, and secured to said vamp and quarter near their abutting edges, whereby a ridge across the foot is dispensed with, and the vamp is secured against splitting by force applied to separate the quarter members.

3. In a front-laced shoe, a quarter divided in front to form a lacing-opening, a continuous vamp, free from said quarter for a suitable distance on each side of said lacing-opening, but with the respective edges abutting, stays secured beneath the quarter members on each side of the lacing-opening, extending to but not under said vamp, a tongue spanning said lacing-opening beneath the quarter, extending a short distance under the vamp, secured to the latter and to the quarter near their abutting edges, and auxiliary stitch-lines *h h*, securing the tongue and quarter members together near the lacing-opening at the point of greatest strain.

In testimony whereof I have signed my name to this specification in the presence of two subscribing witnesses.

HARRY C. JENNEY.
